Des. 202,272
Patented Sept. 14, 1965

202,272

CONTROL KNOB

Thomas Brendgord, Edgewater, N.J., assignor to North Atlantic Industries, Inc., Plainview, N.Y., a corporation of New York

Filed Aug. 18, 1964, Ser. No. 81,341

Term of patent 14 years

(Cl. D26—13)

FIG. 3

FIG. 2

FIG. 4

FIG. 1 is a perspective view of a control knob, showing my new design;

FIG. 2 is a side elevational view thereof;

FIG. 3 is an end elevational view thereof; and

FIG. 4 is a top plan view thereof.

The bottom of the knob, not shown, is substantially plain and unornamented.

I claim:

The ornamental design for control knob, as shown and described.
